(57) **CLAIM**

The ornamental design for a frame for wheeled, manually moveable trash pump, as shown and described.

DESCRIPTION

FIG. 1 is an elevated perspective view of a presently preferred embodiment of frame for wheeled, manually moveable trash pump;

FIG. 2 is a plan view of the left side of a presently preferred embodiment of the frame for wheeled, manually moveable trash pump, the right side plan view being a mirror image thereof;

FIG. 3 is a front view of a presently preferred embodiment of frame for wheeled, manually moveable trash pump;

FIG. 4 is a rear view of a presently preferred embodiment of frame for wheeled, manually moveable trash pump;

FIG. 5 is a top view of a presently preferred embodiment of frame for wheeled, manually moveable trash pump; and,
FIG. 6 is a bottom view of a presently preferred embodiment of frame for wheeled, manually moveable trash pump.
